UNITED STATES PATENT OFFICE.

HARVEY E. BREWER AND MICHAEL H. SHENK, OF ANNVILLE, PENNSYLVANIA.

BLACKSMITHING APPARATUS.

SPECIFICATION forming part of Letters Patent No. 592,193, dated October 19, 1897.

Application filed April 19, 1897. Serial No. 632,826. (No model.)

To all whom it may concern:

Be it known that we, HARVEY E. BREWER and MICHAEL H. SHENK, citizens of the United States, residing at Annville, in the county of 5 Lebanon and State of Pennsylvania, have invented a new and useful Blacksmithing Apparatus, of which the following is a specification.

Our invention relates to a blacksmithing apparatus, and has for its object to provide a compact construction and arrangement of devices for facilitating the operations of forging, drilling, &c.

Further objects and advantages of this invention will appear in the following description, and the novel features thereof will be particularly pointed out in the appended claims.

In the drawings, Figure 1 is a perspective view of a blacksmithing apparatus constructed in accordance with our invention. Fig. 2 is a central longitudinal section of the same with the parts adjusted for forging, and showing in dotted lines the position of the anvil when arranged to form a guide for the drill. Fig. 3 is a transverse vertical section taken in the plane of the drilling mechanism with the parts adjusted for drilling. Fig. 4 is a transverse sectional view of the blast mechanism. Fig. 5 is a similar view of the vise and the contiguous portions of the frame. Fig. 6 is a transverse sectional view of the anvil. Fig. 7 is a detail sectional view of a portion of the anvil to show the latch whereby it is secured in either of its adjusted positions.

Similar numerals of reference indicate corresponding parts in all the figures of the drawings.

The framework of the machine embodying our invention includes a base-plate 1, which is adapted to be secured in a horizontal position to a log or block, such as that illustrated at 2, and front and rear rectangular uprights 3 and 4 are preferably bolted to upstanding flanges 5 at the sides of the base-plate, the rear upright 4 being provided with outwardly-turned feet 6, which are spiked to the support of the base. Also secured to said 50 support are clips 7, which engage the side

edges of the base in advance of the front standard 3.

The base is longitudinally slotted, and the walls of the slot are undercut or dovetailed to form a guide 8 for the reception of the opposite edges of the foot 9 of an anvil 10, and arranged longitudinally in the slot is a feed-screw 11, engaging a nut 12 on the anvil, whereby the rotation of the screw is adapted to impart motion to the anvil in the said guide 55 provided therefor. The means which we have illustrated in the drawings for rotating the feed-screw include a pinion 13 on said screw and an operating crank-gear 14, mounted upon a suitable stub-shaft 15, projecting longitudinally from the base-plate at its rear end, or at any other convenient point which may be found preferable. At the front end of the base-plate the guide is enlarged laterally to form a table 16, upon which the anvil 60 may be turned to occupy any desired angular position, or a position with its horn projecting in either direction, and in order to allow this pivotal or rotary movement of the anvil the nut 12 is provided with a stem or 65 spindle 17, fitting in a suitable socket 18 in the foot of the anvil. It is also desirable to provide for removing the anvil from the base, and hence we employ a key 19, fitted in a transverse opening 20 in the body of the anvil, 70 and engaging a circumferential groove 21 in said stem or spindle. Also, the table is provided with a series of spaced sockets or openings 22 for engagement by a spring-actuated latch carried by the foot of the anvil, 75 whereby the latter may be locked in any desired position with relation to the guide. In the construction illustrated, this latch consists of a bolt 23, a pivotal operating-lever 24, adapted to be depressed at its free end to 80 withdraw the latch-bolt, and an actuating-spring 25.

The front upright 3 carries a vise of which the fixed member 26 is bolted to the contiguous leg of the standard, and is hook-shaped 95 at its lower extremity to form a seat 27 for the lower end of the movable member 28, whereby the bolt 29, which extends through the lower extremities of the vise members, and the adjusting-screw 30, which connects 100

the vise members near their operating extremities, are relieved from downward strain when the upper edges of the jaws of the vise are struck.

5 Connecting the front and rear standards are parallel side bars 31, having vertical offsets at intermediate points, the upper portions of said side bars forming rests for the flanges of the furnace or fire-pot 32, above which is 10 erected a hood 33, to which may be attached a flue 34 to conduct smoke and sparks to a convenient point of discharge. The flange of the furnace is secured by bolts 35, or equivalent means, to the side bars. The lower portions of the side bars are connected by cross-bars 36, which support a blast device for supplying the furnace with a suitable draft. In the construction illustrated this blast device consists of a fan of which the casing comprises 15 an open-ended cylinder 37, having heads 38 and 39, which are removable to give access to the interior of the casing. The casing communicates with the furnace by means of a conductor 40. Mounted in suitable bearings 20 in the heads is a fan-shaft 41, carrying a pulley 42 and a plurality of fan-blades 43, said blades being connected by means of sector-shaped guards 44. The air-inlet openings of the casing are arranged concentric with 25 the fan-shaft, and are exposed by offsetting the bearings of said shaft, whereby the blades of the fan are fed at the center.

Mounted upon an upward extension 4^a of the rear standard is a belt-wheel 45, of which 30 the shaft 46 carries a bevel-pinion 47, said wheel being connected with the belt-pulley of the fan mechanism by means of a belt 48. Any suitable means may be employed for imparting rotary motion to the belt-wheel, which 35 is of large diameter and is peripherally weighted to form a fly-wheel, the means shown in the drawings consisting of a gear 49, meshing with a spur-pinion 50 on the spindle of the belt-wheel and having a belt-pulley 51.

45 52 represents a vertical tool-shaft extending through horizontal portions of the standard 4 and its extension, and provided at its lower end with a tool-socket 53. Loosely fitted upon the upper end of the tool-shaft, 50 above the horizontal portion of said extension 4^a, is a sleeve 54, carrying a fly-wheel 55 and a bevel-gear 56, which is adapted to mesh with the bevel-gear 47, when the sleeve is adjusted upwardly upon the tool-shaft, to bring 55 said parts into operative relation. The sleeve is feathered upon the tool-shaft by means of a key or pin 57, engaging a longitudinal key-slot 58, and the lower end of the sleeve rests upon a follower 59, which is adapted to be 60 moved axially with relation to the tool-shaft by means of a shifting-screw 60, having a terminal hand-wheel 61. This shifting-screw is threaded in an opening in the horizontal portion of the standard extension 4^a, and is 65 tubular to allow the tool-shaft to extend therethrough. A pressure-screw 62 is threaded in a similar opening in a horizontal por-

tion of the standard 4, and is adapted to bear at its lower extremity upon a collar 63 on the tool-shaft, to exert the proper pressure upon the tool to feed the same into the material being drilled, the upper end of the pressure-screw being fitted with a hand-wheel 64.

70 From the above description it will be seen that by lowering the shifting-screw sufficiently to disengage the bevel-pinions the driving mechanism is free to operate the blast device through the belt by which it is connected therewith, and that when it is desired to use the drill the belt may be disengaged 75 from the pulley and the shifting-screw adjusted to bring the bevel-gears into engagement. When it is desired to check the operation of the drill for any purpose, it may be accomplished quickly by adjusting the 80 shifting-screw.

85 The anvil, as hereinbefore described, is adapted for adjustment longitudinally of the base to arrange it either upon the table, where it is adapted for angular or rotary movement, 90 or contiguous to the drill, as shown in dotted lines in Fig. 2; and we preferably provide the anvil with a socket 65, which may be arranged in alignment with the drill-bit 66 to serve as a guide for said bit. At other times this 95 socket is adapted to receive the stem 67 of a shearing-knife 68, as shown in Fig. 1 and in full lines in Fig. 2.

90 The flanges which rise from the lateral edges of the base are preferably provided with openings or perforations 69 for the reception of securing-bolts to fasten various receptacles within reach of the operators, 70 representing a water-box adapted for use in tempering articles in connection with the forging operation, 71 representing a tool or bit receptacle, and 72 an oil-receptacle.

100 It will be seen that the forge is arranged contiguous to the anvil when the latter is arranged upon the turn-table, or at that point 105 in the guide where the anvil is adapted to be adjusted revolubly.

105 It will be understood that in practice various changes in the form, proportion, and the minor details of construction may be resorted to without departing from the spirit or sacrificing any of the advantages of this invention.

Having described our invention, what we claim is—

110 1. A blacksmithing apparatus having a base, a drill and a forge supported by the base, an anvil mounted upon the base for movement into operative relation with the drill and forge, and means for adjusting the anvil, 115 substantially as specified.

115 2. A blacksmithing apparatus having a base provided with a longitudinal guide, an anvil mounted in said guide, adjusting devices connected with the anvil for varying its position 120 in the guide, and a drill and a forge supported by the base on the line of movement of the anvil, substantially as specified.

120 3. A blacksmithing apparatus having a base

provided with a cross-sectionally-dovetailed guide, a drilling mechanism and a forge supported by the base above the guide, an anvil having its foot mounted in said guide, and 5 adjusting devices for the anvil whereby it may be caused to traverse the guide beneath the forge and the drilling mechanism, substantially as specified.

4. A blacksmithing apparatus having a 10 movable anvil, a guide for the foot of the anvil, said guide communicating at one end with a turn-table upon which the anvil may be revolubly adjusted, means for moving the anvil in said guide, and a drill and forge arranged upon the line of the guide, substantially as specified.

5. A blacksmithing apparatus having a base 15 provided with a longitudinal guide and a communicating turn-table, an anvil revolubly seated upon the turn-table and adapted to fit in said guide for longitudinal adjustment, means for holding the anvil at the desired angular and longitudinal adjustment, and a drill and forge arranged upon the line of the 20 guide, substantially as specified.

6. A blacksmithing apparatus having a base 25 provided with a longitudinal guide having an enlargement forming a turn-table, an anvil having its foot mounted in said guide, a feed-screw arranged parallel with the guide, a nut engaged by the feed-screw and having a stem or spindle revolubly mounted upon the anvil, whereby the latter is capable of revoluble adjustment, and means for rotating the feed-screw, substantially as specified.

7. A blacksmithing apparatus having a base 30 provided with a longitudinal guide and a terminal enlargement forming a turn-table, a feed-screw arranged parallel with the guide, a feed-nut engaged by the feed-screw and having a stem or spindle provided with a circumferential groove, an anvil adapted to traverse said guide and having a central bore or opening to receive the stem or spindle of 35 the feed-nut, a key fitted in a transverse opening in the anvil and engaging said groove, and means for rotating the feed-screw, substantially as specified.

8. A blacksmithing apparatus having a base 40 provided with a longitudinal guide and a communicating turn-table, an anvil-carrying device and means for operating the same in a path parallel with said guide, and an anvil revolubly and removably mounted upon the 45 anvil-carrying device, and adapted for rotary adjustment when arranged on the turn-table, substantially as specified.

9. A blacksmithing apparatus having a base 50 provided with a longitudinal cross-sectionally- undercut guide having a lateral enlargement forming a turn-table, an anvil-carrying device and means for operating the same in a path parallel with the guide, and an anvil 55 revolubly and removably mounted upon the anvil-carrying device, and having feet to engage the undercut walls of the guide, and disengaged therefrom when arranged in said enlargement of the guide, substantially as specified.

10. A blacksmithing apparatus having a 70 base provided with a longitudinal guide, a drill located contiguous to one end of and above the guide, a forge located contiguous to the other end of the guide, an anvil mounted in the guide and provided with a vertical 75 shearing-knife socket adapted to be alined with the tool-shaft of the drill, to form a drill-socket, and feeding mechanism for moving the anvil, substantially as specified.

11. A blacksmithing apparatus having a 80 base provided with a longitudinal guide, an anvil mounted in said guide, feed mechanism for adjusting the anvil, front and rear standards rising from the base, drilling mechanism supported by the rear standard, a forge supported by the front standard, a blast mechanism, and operating devices for the blast and drilling mechanisms, substantially as specified.

12. The combination with an operating-shaft having a gear, of a tool-shaft, a second gear feathered upon the tool-shaft and adapted to mesh with the first-named gear, and a tubular shifting-screw having a hand-wheel, arranged concentric with the tool-shaft and 95 threaded in a fixed object, said shifting-screw being terminally arranged in operative relation with said second gear, substantially as specified.

13. The combination with an operating-shaft having a gear, of a tool-shaft, a second gear feathered upon the tool-shaft and adapted to mesh with the first-named gear, a shifting-screw having a hand-wheel, arranged concentric with the tool-shaft and threaded in a 105 fixed object, and a follower interposed between the shifting-screw and said second gear, substantially as specified.

14. The combination with an operating-shaft and a gear carried thereby, of a tool-shaft provided at one end with a fly-wheel, a sleeve feathered upon the tool-shaft and carrying a second gear to mesh with the first-named gear, and a tubular shifting-screw having a hand-wheel, arranged concentric with 110 the tool-shaft at an intermediate point, and threaded in a fixed object, said shifting-screw being terminally arranged in operative relation with said second-named gear, substantially as specified.

In testimony that we claim the foregoing as our own we have hereto affixed our signatures in the presence of two witnesses.
